UNITED STATES PATENT OFFICE

JACOB SCHWARTZ, OF TERRE HAUTE, INDIANA, ASSIGNOR TO AMERICAN ART WOOD PRODUCTS CORP., OF TERRE HAUTE, INDIANA, A CORPORATION OF INDIANA

DESIGN FOR A LAMP OR ANALOGOUS ARTICLE

Application filed October 14, 1931. Serial No. 41,381. Term of patent 3½ years.

To all whom it may concern:

Be it known that I, JACOB SCHWARTZ, a citizen of the United States, residing at Terre Haute, in the county of Vigo and State of Indiana, have invented a new, original, and ornamental Design for a Lamp or Analogous Article, of which the following is a specification, reference being had to the accompanying drawings forming part thereof, wherein—

Fig. 2 is a view in horizontal section substantially on line 2—2 of Figure 1.

I claim:

The ornamental design for a lamp or analogous article, as shown.

JACOB SCHWARTZ.
